(57) **CLAIM**

The ornamental design for a vehicle grille, as shown and described.

DESCRIPTION

FIG. 1 is a top, right, front perspective view of the vehicle grille;

FIG. 2 is a bottom, right, front perspective view thereof;

FIG. 3 is a front view thereof;

FIG. 4 is a rear view thereof;

FIG. 5 is a top view thereof;

FIG. 6 is a bottom view thereof;

FIG. 7 is a left-side view thereof; and,

FIG. 8 is a right-side view thereof.

The dashed lines in the drawings depict portions of the vehicle grille that form no part of the claimed design. The boundary line, consisting of dash-dot-dash lines, indicates the boundary between the claim and portions that are not part of the claimed design.

1 Claim, 8 Drawing Sheets
